(57) **CLAIM**

The ornamental design for a stirrer as shown and described.

DESCRIPTION

FIG. 1 is a top perspective view of the stirrer showing my new design.

FIG. 2 is a bottom perspective view thereof.

FIG. 3 is a side elevation view thereof.

FIG. 4 is another side elevation view thereof.

FIG. 5 is a top view thereof.

FIG. 6 is a bottom view thereof; and,

FIG. 7 is a perspective view thereof, shown in a use condition.

The broken lines are shown for environmental purposes only and form no part of the claimed invention.

1 Claim, 4 Drawing Sheets

FIG. 3

FIG. 4

FIG. 5

FIG. 6

FIG. 7
